The ornamental design for the body harness apparatus, as shown and described.

DESCRIPTION

FIG. 1 is a front elevational view of the body harness apparatus according my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is an unfolded view thereof.

The broken line showing of a ring in FIGS. 3 and 4 is for illustrative purposes only and forms no part of the claimed design.

The broken lines on the straps in FIGS. 1, 2 and 7 are understood to represent stitching. The fragmentary criss-cross pattern shown in the drawing is understood to represent fabric and is repeated uniformly throughout the areas shown.

The straps have been shown broken away in FIG. 7 in the drawing to indicate indeterminate length.
